MOLDER'S SHOE

Filed Jan. 10, 1923

Inventor:
A. L. Rohrbacher, Jr.

by Leo W. Goldard
atty.

UNITED STATES PATENT OFFICE.

ALBERT L. ROHRBACHER, JR., OF BOSTON, MASSACHUSETTS.

MOLDER'S SHOE.

Application filed January 10, 1923. Serial No. 611,858.

To all whom it may concern:

Be it known that I, ALBERT L. ROHRBACHER, Jr., a citizen of the United States, and resident of Boston, in the county of Suffolk and State of Massachusetts, have invented certain new and useful Improvements in Molders' Shoes, of which the following is a specification.

This invention relates to shoes and is particularly intended to provide a simple and effective construction by which the shoe top or upper is properly vented or cut to permit the easy insertion of the foot and the easy withdrawal of the shoe, while making proper provision for interlocking the edges of the vent or opening by an instantly detachable locking means so that no time is lost in releasing the vent where it is of great importance to instantly strip the shoe from the foot.

It is well known that in foundries or shops where molten iron or metal is handled, in spite of all precautions, the molten metal is often dropped into the boot or shoe of the operative, thereby causing serious burns and injury. In such an emergency it is of the utmost importance that nothing should impede the instantaneous removal of the shoe, while at the same time effective provision should be made for normally keeping the shoe closed as effectively as possible against the inflow of such metal.

The present invention deals with this problem and consists essentially in the combination with a shoe bottom and upper whose top is slit preferably on the side to form a vent extending to the top of the shoe, two flaps of material next to the vent being provided with intermatching closing means normally held in interlocked relation by means of a locking member in the form of a flexible pin or key or its equivalent.

This and other features of the invention will be set forth in the following specification and will be defined in the claims hereto annexed.

In the accompanying drawings I have shown a convenient and satisfactory construction and arrangement embodying the principles of this invention, in which:

Figure 1 is a side elevation of a shoe constructed in accordance with my invention, the vent being locked in closed position.

Figure 2 is a plan view of the vented side of the top or upper of the shoe.

Figure 3 is an enlarged detail showing

more clearly the details of construction of the vent-closing and locking means.

In the practice of this invention, according to the form illustrated, the molder's shoe is of suitable and usual construction so far as the sole 1, and the heel 2, constituting the bottom, and so far as the vamp 3 comprising the forepart of the upper are concerned.

The top portion 4 of the upper is vented, preferably along one side from the top edge downward to or nearly to the shoe bottom.

One of the edge portions of the two flaps at the vent is formed with an extension or tongue 6 to pass inside the other flap 5 and overlap the same so as to completely close the vent when the shoe is on the foot, just as the ordinary tongue of a lace shoe closes the vent, although the vent-closing tongue may be formed in any suitable manner. To the respective flaps 4 and 5 adjacent to the vent are secured series of intermatching metal loops 8 and 9 provided with overlapping eye portions 8^a, 9^a which, when the vent is closed register or align with each other from top to bottom so as to permit the insertion of a suitable locking member or pin 7 which is preferably quite flexible, and is provided at its top with a knob or enlargement 7^a to permit quick handling and prevent its being inserted too far to be readily grasped and removed when occasion requires. This locking member is preferably made of raw hide or other flexible material to allow the shoe top to conform closely to the contour of that portion of the foot adjacent to the vent.

As actually shown the loops 8 are made of wire, both arms of the loop being passed through the flap 4 adjacent to the tongue portion from the outside and being bent and clinched to hold them in place, the clinched portions being preferably offset or staggered out of vertical alignment so as to avoid bringing the receiving perforations in the leather too near together.

The loop 9, also in this case shown as made of wire construction, may have one arm passed inside the flap 5 and the other outside, the ends penetrating the material from opposite sides, and being clinched to prevent withdrawal. It will be understood that the object of passing the arms 8 of the wire loops through from the outside is to permit the formation of an integral extension of the edge adjacent to the vent to

form a closing tongue integral with the flap 4 of the boot top. The lower end of the locking member 7 is preferably pointed to permit ready insertion.

5 The two sets of loops 8 and 9 are so spaced and arranged that when the flaps of the vent are brought together in normal vent-closing position the eyes 8^a, 9^a, intermatch and register one with the other, permitting the ready insertion of the flexible pin. In case the instant removal of the shoe is necessary all that is required is to seize the upper end or knob 7^a of the locking member which can be instantly withdrawn, allowing the vent to instantly open as the shoe is withdrawn.

What I claim is:

1. A molder's shoe embracing in its construction a shoe bottom, a vamp, and a top 20 joined to said vamp and upper and vented from its upper edge to the bottom and forming flaps lapping one inside of the other, a series of intermatching metallic loops whose ends are clenched through the flap portions of the vent and whose inter-

mediate portions are formed into eyes arranged to register with one another when the vent is closed, and a flexible pin adapted to be inserted and instantly removable from said registering eyes, substantially as 30 described.

2. A molder's shoe embracing in its construction a bottom, a vamp and a top joined to the vamp and to the bottom and having a vent extending vertically from its upper 35 edge to the bottom to form separable flaps one of said flaps being overlapped inside the other, a series of metallic loops whose ends are clenched through the overlapping flap from the outside, and a cooperating series 40 of metallic loops clenched through the opposite flap portion of the top so as to intermatch and register with the first mentioned metallic loops, and a flexible locking pin inserted through both sets of loops when 45 they are placed in registry with each other, substantially as described.

In witness whereof, I have subscribed the above specification.

ALBERT L. ROHRBACHER, JR.
